UNITED STATES PATENT OFFICE

164,936

ANIMATED DECORATIVE LAMP

Aubrey B. Leech, Los Angeles, Calif.

Application May 8, 1950, Serial No. 9,777

Term of patent 7 years

(Cl. D48—20)

To all whom it may concern:

Be it known that I, Aubrey B. Leech, a citizen of the United States of America, residing in the city of Los Angeles, in the county of Los Angeles, State of California, have invented a new, original, and ornamental Design for an Animated Decorative Lamp, of which the following is a specification, reference being had to the accompanying drawings, forming a part thereof.

Fig. 1 is a perspective view of an animated decorative lamp, showing my new design;

Fig. 2 is a top plan view thereof;

Fig. 3 is a panoramic view of the outer cylinder;

Fig. 4 is a panoramic view of the intermediate cylinder;

Fig. 5 is a perspective panoramic view of the innermost cylinder;

Fig. 6 is a perspective view partially broken away showing the relative position of the various screen or cylinders; and

Fig. 7 is a bottom plan view.

I claim:

The ornamental design for an animated decorative lamp, substantially as shown.

AUBREY B. LEECH.
